(57) **CLAIM**

The ornamental design for an animal paw grip, as shown and described.

DESCRIPTION

FIG. 1 is a top, front, left perspective view of an animal paw grip, showing my new design in a first configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, right, rear perspective view thereof; and, FIG. 9 is a front elevation view of the animal paw grip of FIG. 1 in a second configuration, showing the surface in an open state, revealing the base.

In FIG. 9, the broken lines depict elements of the animal paw grips that form no part of the claimed design.
